SUCTION CLEANER

Frederick Riebel, Jr., Toledo, Ohio, assignor to
Air-Way Electric Appliance Corporation, To-
ledo, Ohio, a corporation of Delaware

Original application February 27, 1933, Serial No.
658,684. Divided and this application April 3,
1934, Serial No. 718,826

8 Claims. (Cl. 15—155)

This invention relates to suction cleaners of the type wherein the nozzle or floor tool is resiliently mounted on rollers disposed at its ends, and has for its object to provide means whereby the floor tool may be adjusted for height to any of a series of normal riding positions determined by the balance between the weight of the floor tool and the tension of the resilient portions of the mountings when flexed under said weight, below any one of which positions the floor tool may be depressed under manual pressure.

More specifically, it is my object to provide a resiliently mounted floor tool wherein adjustment of the lifting tension of the resilient mounting which connects a supporting roller to the floor tool, is accomplished by adjusting the height of the roller relative to the mounting without interfering with the ability of the mounting to give under increased weight on pressure on the floor tool. To this end, the adjusting means is interposed between the roller and a relatively rigid portion of the mounting, the resilient member in turn being interposed between this relatively rigid portion of the mounting and the floor tool.

Other objects of the invention will appear in the following detailed description of the invention, illustrated in the accompanying drawing, in which:

Fig. 1 is a perspective view of a cleaner embodying the invention.

Fig. 2 is a sectional view taken longitudinally thru one end of the floor tool thereof.

Fig. 3 is a plan view of the roller and its mounting.

Fig. 4 is a sectional view taken on the line 4—4 of Fig. 2.

Fig. 5 is a sectional view, similar to Fig. 2, of a modified form of the invention.

Fig. 6 is a plan view of the roller and its mounting, of Fig. 5.

The floor tool 30 is supported by a pair of rollers 31 one at each end of the tool. The rollers 31 are attached to mountings 32 which in turn are attached to the floor tool. Each mounting 32 includes a resilient portion which serves to carry the weight of the cleaner to the roller, and which allows the tool to be depressed below a normal riding position determined by the balance between the weight of the cleaner 33 and the tension in the resilient portion of the mounting.

In the form shown in Figs. 2, 3, and 4, the mounting is in the form of a relatively non-resilient bracket 34 and a leaf spring 35 secured to the bracket at the end thereof opposite the roller 31, the spring diverging from the bracket

so that its free end is spaced therefrom a substantial distance, sufficient to provide room for relative movement of the bracket toward the spring to provide for the aforesaid manual depression.

The floor tool 30 has end sockets 36 which are wedge-shaped to receive the V shaped mountings. The free ends of the bracket 34 and spring 35 project out of the socket. A screw 21, mounted in the socket, projects through an opening in the spring to retain the mounting against end-wise removal from the socket.

The free end of the bracket 34 has a down-bent vertical arm 31. The roller 31 is journaled on a hub assembly 38 which in turn is secured to a carriage 39. The carriage 39 is slidably mounted on the arm 31, being C-shaped in cross section so as to embrace the arm.

A spring latch 40, secured to the bracket 34, engages any one of a series of four notches 41 in the carriage 39, to hold the roller 31 in any of four positions relative to the bracket 34.

Changing of the position of the roller relative to the bracket will result in a corresponding change in the normal riding position of the floor tool relative to the floor. From any of the several normal riding positions thus determined, the floor tool may be depressed against the tension of the spring 35.

Furthermore, the range of possible depression below normal riding position is not varied by a change in adjustment in this form of the invention, an element of advantage which distinguishes the present invention from those which are covered in my Patents Nos. 1,899,107, 1,899,108, and 1,899,423. The present application is a continuation in part of the application for those patents and a division of application Serial No. 658,684, filed February 27, 1933, which has matured into Patent No. 2,002,509.

Another advantage of the present invention, by which it is distinguished, is the fact that the roller may be removed from arm 31 by releasing the latch 40. Since the roller is of soft rubber, and subject to wear, the ability to replace the roller without replacing the mounting 32, is obviously an advantage.

The latch 40 and cooperating notches 41 constitute both an adjusting means, carrying the weight of the cleaner from the bracket to the carriage and means to secure the roller to the bracket.

Fig. 5 illustrates another form of the invention in which the roller 31 may be adjusted relative to the bracket 34a.

In this form, the floor tool 30 has the same socket 36, and the bracket 34a is secured at one end to the leaf spring 35, which is retained by the screw 27.

5 The roller 31 is mounted on an arm 37a which is formed with a portion 34b bent to align with the bracket 34a. The arm 37a and portion 34b constitute a carriage which is movably mounted on the bracket 34a by means of a hinge 42. An 10 adjusting element 43, on the member 34b, engages a coacting element 44 on the bracket 34a, the latter being preferably in the form of a tongue formed on the bracket 34a and projecting beyond the hinge 42. The adjusting element 15 may be a screw, threaded through a sleeve 45 secured to the member 34b. The coacting elements 43 and 44 carry the weight of the cleaner from the bracket 34a to the roller carriage 37a.

20 If the member 34b is considered as part of the bracket, then the adjustment is accomplished by varying the angular relation of the hinged members of the bracket, by adjusting means spanning the hinge. This form of the invention also possesses the advantage that the change in adjustment does not vary the range of possible depression below normal riding position. The clearance between the hinge 42 and the spring 35 is unaffected by a change in adjustment.

25 30 I claim as my invention:

1. In a suction cleaner, a floor tool, a mounting including a bracket movably attached to the floor tool and having a projecting portion, a roller carrying part movably connected solely to said projecting portion, a roller journalled on said part, and adjusting means connecting said part to the bracket, serving to carry the weight of the cleaner from the bracket to said part, and a spring interposed between the bracket and the floor tool and resiliently carrying the weight of the floor tool to the bracket, whereby the floor tool may be manually depressed below any one of a series of normal riding positions determined by the balance between the weight of the cleaner and the tension in said spring when flexed under said weight, and the position of adjustment of said part.

35 40 45 50 55 60 65 70 75 2. In a suction cleaner, a floor tool, a pair of mountings, each including a bracket movably attached to the floor tool one at either end of the floor tool, projecting beyond said end, and having a projecting vertical portion, a carriage slideable on said vertical portion, a roller journalled on said carriage, and adjusting means connecting said carriage to the bracket, serving to carry the weight of the cleaner from the bracket to the carriage, and to provide adjustment of the height of the carriage relative to the bracket, and a spring interposed between the bracket and the floor tool and resiliently carrying the weight of the floor tool to the bracket, whereby the floor tool may be manually depressed below any one of a series of normal riding positions determined by the balance between the weight of the cleaner and the tension in said spring when flexed under said weight, and the position of adjustment of said carriage.

3. In a suction cleaner, a floor tool, a roller mounting including a bracket movably attached to the floor tool, a roller carrying part hinged to the bracket, for swinging movement relative to said bracket, a roller journalled on said part near the swinging end thereof, adjusting means acting between said bracket and said part, carrying the weight of the cleaner from the bracket to said

part, and a spring interposed between the bracket and the floor tool and resiliently carrying the weight of the floor tool to the bracket, whereby the floor tool may be manually depressed below any one of a series of normal riding positions determined by the balance between the weight of the cleaner and the tension in said spring when flexed under said weight, and the position of adjustment of said part.

4. In a suction cleaner, a floor tool, a mounting including a bracket movably attached to the floor tool, a roller carrying part movably connected solely to the bracket, a roller journalled on said part, and adjusting means acting between said part and the bracket, serving to carry the weight of the cleaner from the bracket to said part, and a spring interposed between the bracket and the floor tool and resiliently carrying the weight of the floor tool to the bracket, whereby the floor tool may be manually depressed below any one of a series of normal riding positions determined by the balance between the weight of the cleaner and the tension in said spring when flexed under said weight, and the position of adjustment of said part.

5. In a suction cleaner, a floor tool, a mounting including a bracket one end of which is fulcrumed relative to the floor tool, so as to allow the bracket to swing vertically relative to the floor tool, a roller carrying part movably connected to the other end of the bracket, a roller journalled on said part, adjusting means acting between said part and the bracket, serving to carry the weight of the cleaner from the bracket to said part, and a spring interposed between the bracket and the floor tool and resiliently carrying the weight of the floor tool to the bracket, whereby the floor tool may be manually depressed below any one of a series of normal riding positions determined by the balance between the weight of the cleaner and the tension in said spring when flexed under said weight, and the position of adjustment of said part.

6. In a suction cleaner, a floor tool, a mounting including a bracket movably attached to the floor tool and having a projecting vertical portion, a carriage slideable on said vertical portion, a roller journalled on said carriage, and adjusting means connecting said carriage to the bracket, serving to carry the weight of the cleaner from the bracket to the carriage, and to provide adjustment of the height of the carriage relative to the bracket, and a spring interposed between the bracket and the floor tool and resiliently carrying the weight of the floor tool to the bracket, whereby the floor tool may be manually depressed below any one of a series of normal riding positions determined by the balance between the weight of the cleaner and the tension in said spring when flexed under said weight, and the position of adjustment of said carriage.

7. In a suction cleaner, a floor tool, a mounting attached thereto comprising a bracket having a projecting non-horizontal portion, a carriage movably mounted on said portion for up and down adjustment relative to the bracket, a roller journalled on said carriage, and adjusting means connecting said carriage to the bracket, serving to carry the weight of the cleaner from the bracket to the carriage, and to provide adjustment of the height of the carriage relative to the bracket, and a spring interposed between the bracket and the floor tool and resiliently carrying the weight of the floor tool to the bracket, whereby the floor tool may be manually depressed be-

5 low any one of a series of normal riding positions determined by the balance between the weight of the cleaner and the tension in said spring when flexed under said weight, and the position of adjustment of said carriage.

8. In a suction cleaner, a floor tool, a mounting including a bracket one end of which is fulcrumed relative to the floor tool, so as to allow the bracket to swing vertically relative to the floor tool, a roller carrying part hinged to the other end of the bracket, for swinging movement relative to said bracket, a roller journalled on said part near the swinging end thereof, adjusting

means acting between said bracket and said part, carrying the weight of the cleaner from the bracket to said part, and a spring interposed between the bracket and the floor tool and resiliently carrying the weight of the floor tool to the bracket, whereby the floor tool may be manually depressed below any one of a series of normal riding positions determined by the balance between the weight of the cleaner and the tension in said spring when flexed under said weight, 10 and the position of adjustment of said part.
